UNITED STATES PATENT OFFICE.

JOSEPH WEBER, OF BROOKLYN, NEW YORK.

ELECTROMAGNET AND ARMATURE.

SPECIFICATION forming part of Letters Patent No. 784,456, dated March 7, 1905.

Application filed May 1, 1900. Renewed August 31, 1904. Serial No. 222,903.

To all whom it may concern:

Be it known that I, JOSEPH WEBER, a citizen of the United States, residing in Brooklyn borough, in the county of Kings and State of New York, have invented certain new and useful Improvements in Electromagnets and Armatures; and I do hereby declare the following to be a full, clear, and exact description of the invention, such as will enable others skilled in the art to which it appertains to make and use the same.

The object of my invention is to produce improvements in electromagnets and armatures whereby the efficiency of an electromagnet or plurality of electromagnets in producing movement of an armature is augmented and whereby a plurality of electromagnets may be enabled to act upon a common armature with economy of space and with equal distribution of power among the individual electromagnets.

Heretofore a common armature adapted to be actuated by a plurality of electromagnets has been mounted so as to swing in a plane parallel to its longitudinal axis, one end of the armature acting as a fulcrum or fixed support and the other end performing the required movement. This arrangement is objectionable both because of unnecessary space required for the sweep of the armature and because since the magnets attract the armature unequally, owing to the unequal distance between the armature and the magnets, respectively, the greatest efficiency of the several magnets is not rendered available, especially for producing the initial movement of the armature. By my invention the armature is movably supported upon an edge parallel to its longitudinal axis and preferably in such juxtaposition to the several magnets of which it is the armature as to utilize equally the efficiency of the several magnets throughout its entire movement. The arc of movement of the free edge of my armature being necessarily limited in proportion to the size of the electromagnets I contemplate the employment upon such an armature of an arm extending at an angle to the longitudinal axis of the armature. This arm may be obliquely disposed

to the armature or at any preferred angle 5° thereto.

In the accompanying drawings, Figure 1 is a perspective view of three sets of electromagnets equipped with my improved armature and assembled for the purpose of illustration with three keys of a musical instrument which the armatures are designed to operate respectively. Fig. 2 is a front end view of the subject-matter of Fig. 1. Fig. 3 illustrates an end view of an armature, showing a modified manner of assembling the same with respect to a magnet. Figs. 4 and 5 illustrate, respectively, further modifications of the subject-matter of Fig. 3. Fig. 6 illustrates an armature-supporting collar adapted to be applied to an electromagnet-core for operatively assembling my armature with respect thereto. Fig. 7 illustrates in perspective an electromagnet and a portion of its armature, as shown in Figs. 1 and 2.

Referring to the numerals on the drawings, 1, 2, and 3 illustrate a plurality of electromagnets adapted to actuate a common armature 4, three sets of magnets and three armatures common to the respective sets being shown. The individuals of each set of magnets are assembled so as to bring their respective axes into a common plane. Their cores may be, for example, secured to a bar 5 for that purpose. As illustrated in Figs. 1 and 2, the magnets are shown as adapted to operate keys 6 of a musical instrument, the bars being assembled above the keys at suitable distances and provided with upturned terminals 7, by which they may be secured to a part of the frame of the instrument. Each of the armatures is shown as provided with an arm 8, projecting at an angle from the armature and operatively connected with its appropriate key, as by a connecting-piece 9.

The illustration of the application of my invention to a musical instrument is made solely for the purpose of exemplifying one of its utilities, and the means of assembling the electromagnets and the mode or purpose of utilizing the movement of the armature have no direct bearing upon my present invention set forth in this application.

From a comparison of Figs. 1 and 2 it may be understood that my invention consists, essentially, in pivotally mounting an armature upon an axis parallel to its longitudinal axis 5 and in operative proximity to the core of an electromagnet, whereby the energizing of the magnet will produce movement of the armature upon its pivot. I prefer to provide the pivotal support for an armature upon or near 10 the outer edges of the faces of the cores of the magnets, it being assumed that the free or unsupported edge of the armature is normally sustained by suitable means out of contact with the cores of the magnets, but is 15 adapted to be attracted toward them by the energizing of the magnets, and thereby to produce the required movement of the armature. In the drawings the armatures are sustained in the position described by their connection 20 with the keys 6, respectively, the keys being, as is usual in keyed musical instruments, balanced or spring-supported in determinate positions.

A variety of means may be employed for 25 pivotally supporting the armature in proper relations with respect to the core or cores of its magnet or magnets. For instance, in Figs. 1, 2, and 7 each core 10 is shown as provided at one edge with a nob or projection 11, which 30 fits into a corresponding recess 12 near that edge of the armature which is designed to be pivotally supported. It is not, however, essential that the edge of the armature and the edge of the core should exactly make contact. 35 For example, in Fig. 3 an electromagnet 14 is provided upon its top with a standard 15, to which, as by a pintle 16, the armature 17 is pivoted within operative relations to the core 18. In Fig. 4 a magnet 20, provided with a core 40 21, is provided with a recess in its face to accommodate a projection 22 upon the bottom of the armature 23. In Fig. 5 a magnet 24 is shown as provided with a core 25, beyond the outer edge of which projects a pin 26 parallel 45 to its axis, the armature 27 being provided with a beveled edge 28, which works in the angle between the pin 26 and the face of the core 25. The pin 26 may be provided upon the core, as by means of a collar 29, 50 (shown in Fig. 6,) which may be shrunk upon or otherwise secured to the core, the end of which may be reduced, if desired, to accommodate it.

In the foregoing specification it is assumed

that the several magnets are provided with the usual coils for transmitting electrical energy and are connected in circuit with a suitable source of such energy. There being nothing novel in the construction of the magnets, it is unnecessary to illustrate or describe in detail 60 their structure or relative assemblage in electric circuit. Suffice it to say in this connection that by the making and breaking of each circuit each set of magnets in the circuit is adapted alternately to attract and release their 65 respective armatures, and by reason of the fact that the armature bears the same relative position to the core of each of the electromagnets of a set each of the magnets therefore operates upon it at the same time with equal 70 intensity, proportionate, of course, to the respective powers of the magnets.

What I claim is—

1. The combination with an electromagnet, of a disconnected armature loosely mounted 75 upon the core of a magnet, to oscillate about an axis parallel to the longitudinal axis of the armature, a projection on one part and a co-operating member operatively arranged with relation to the said projection for pivotally 80 engaging the armature and core at their points of connection, as set forth.

2. The combination with an electromagnet, of a disconnected armature loosely mounted upon the core of the magnet to oscillate about 85 an axis parallel to the longitudinal axis of the armature, an arm projecting at an angle from the armature and a detachable pivotal connection between the armature and core to one side of the axial center of the core.

3. The combination with an electromagnet, of a disconnected armature loosely mounted upon the core of the magnet to oscillate about an axis parallel to the longitudinal axis of the armature, an arm projecting at an angle from 95 the armature and a detachable pivotal connection between the armature and core to one side of the axial center of the core and parallel with said core, and a connection between a lateral offset of the armature and its appropriate key.

In testimony whereof I affix my signature in presence of two witnesses.

JOSEPH WEBER.
